UNITED STATES PATENT OFFICE.

FRED A. PUTNAM, OF MELROSE, AND CHARLES F. ROBBINS, OF ABINGTON, MASSACHUSETTS, ASSIGNORS TO LABEM MACHINE COMPANY, OF BOSTON, MASSACHUSETTS, A CORPORATION OF MASSACHUSETTS.

PRINTING-MACHINE.

1,279,904.

Specification of Letters Patent. Patented Sept. 24, 1918.

Application filed November 9, 1916. Serial No. 130,447.

To all whom it may concern:

Be it known that we, FRED A. PUTNAM, a citizen of the United States, residing at Melrose, county of Middlesex, State of Massachusetts, and CHARLES F. ROBBINS, a citizen of the United States, residing at Abington, county of Plymouth, State of Massachusetts, have invented an Improvement in Printing-Machines, of which the following 10 description, in connection with the accompanying drawing, is a specification, like characters on the drawing representing like parts.

This invention relates to printing machines of that type having a plurality of platens and a plurality of type beds arranged about a common center and constructed so that the platens and type beds may move relative to each other about the 15 common center thereby bringing the platens successively into printing position relative to each type bed, and the object of the invention is to provide a novel machine of this type in which the platens are arranged in a 20 circle outside of the type beds so that they are easily accessible for placing thereon the material on which the printed impression is to be made, and also to provide a machine of this type having a novel means for moving the type beds toward and from the 25 platens, and for giving relative movement to the platens and type beds to bring the 30 platens and type beds successively into operative position, and otherwise to improve 35 machines of this type, all as will be more fully hereinafter set forth.

In order to give an understanding of our invention, we have illustrated in the drawings a selected embodiment thereof which 40 will now be described, after which the novel features will be pointed out in the appended claims.

In the drawings, Figure 1 is a vertical 45 sectional view of a device embodying our invention;

Fig. 2 is a top plan view thereof;

Fig. 3 is a view showing the brake for the platen-supporting member;

Fig. 4 is a vertical section on the line 4—4, 50 Fig. 1, with the type carrier removed;

Fig. 5 is a section on the line 5—5, Fig. 1;

Fig. 6 is a section on the line 6—6, Fig. 5;

Fig. 7 is a sectional view on the line 7—7, 55 Fig. 1;

Fig. 8 is a fragmentary sectional view 55 showing one type carrier separated from its platen;

Fig. 9 is a side view of the actuating mechanism for the pawl carrier;

Fig. 10 is a detail of the means for centering each type carrier as it moves toward the platen,

Fig. 11 is a fragmentary view showing the pawl for actuating the platen-supporting member,

Fig. 12 is a section on the line 12—12, 65 Fig. 11.

As stated above, the printing machine herein shown is of that type comprising a plurality of platens and a plurality of type 70 carriers arranged about a center, and means to cause a relative rotary movement between the platens and type carriers about said center so that the platens are brought successively into printing position with each 75 type carrier.

In the present embodiment of our invention, the platens are mounted upon a rotatable platen-supporting member and are situated outside of the type carriers with their 80 operative faces directed toward the center of rotation. The type carriers, on the other hand, are situated within the circle of movement of the platens and are arranged so that the type face outwardly and the type 85 carriers are constructed to be moved in a radial direction toward and from the platens.

The platens and type carriers are supported upon a suitable frame or standards indicated generally at 1, and this frame has 90 at its upper end a head 2 on which a plurality of type carriers are sustained for horizontal radial movement. The platens are supported on a rotatable platen-supporting member 3 which is rotatably mounted on 95 the standard 1, said standard being provided with the annular shoulder 4 on which the platen-supporting member rests. Any number of platens and type carriers may be employed, depending upon the character of 100 the printing to be done. In the present embodiment of our invention, we have illustrated four platens and four type carriers. The platen-supporting member is formed with four radially-extending arms 5, on the 105 outer end of each one of which is secured a bracket 6 carrying a platen 7 against which rests the paper or other material to

be printed on. Each platen 7 is preferably adjustably secured to its bracket so that it can be adjusted vertically thereon, and each bracket is provided with clamping screws 8 5 by which the corresponding platen is held in proper adjusted position.

Each platen has associated therewith a retaining member 9 which yieldingly holds the paper, cloth or other material to be printed 10 on against the platen during the printing operation. Each retaining member 9 is in the form of a forked device pivotally mounted at 10 to the corresponding arm 5 and provided with a projecting finger 11 which is 15 acted upon by a spring 12 that yieldingly holds the retaining member against the platen.

The type carriers, of which there are four in number, are indicated at 13, 13^a, and 20 each type carrier is slidably mounted in guideways 14 formed on the head 2. These guideways 14 extend radially so that the type carriers 13 move in a radial direction toward and from the platens. The type by 25 which the printing is done may be secured to the type carriers 13 in any suitable way. In the present invention we have shown three of the type carriers 13 as constructed to support a "form" or type block containing 30 fixed type characters and one of the type carriers constructed to support adjustable type. Fig. 4 shows one of the type carriers designed to support the fixed type. The fixed type is shown in the form of a 35 type block 15 supported in the frame 16 that in turn is secured to the type carrier 13 by suitable screws 17. A type carrier adapted to support adjustable type is shown at the left in Fig. 1 and in Fig. 5. The adjustable type are illustrated in the form of type disks 18, each carrying on its periphery a plurality of type characters 19, and these disks are rotatably mounted upon a hollow shaft 20 which is sustained in bearings 21 40 carried by the type carrier 13^a. The bearings are mounted for vertical adjustment on the type carrier 13^a and are held in adjusted position by the clamping screws 22. For adjusting the type disks, we propose to 45 make the shaft 20 slidable longitudinally through the bearings 21 and to provide said shaft with a lug or projection 23 that is adapted to be entered into notches 24 formed on the interior of the type disks 18. The shaft 20 is provided with a handle 25 at one end by which it may be operated. To adjust any particular type disks, the shaft will be shifted longitudinally to bring the lug 23 thereon into a notch 24 in the particular disk to be adjusted, after which turning 55 movement of the shaft will result in turning the type disk.

The type carriers are given their horizontal radial movement toward and from the platen by means of a vertically-movable

plunger 26 which reciprocates in the standard 1. This plunger is operated by a driving shaft 27 carried by the frame 1, said shaft being provided with the crank 28 which is connected to the plunger by the connecting rod 29. The connections between the plunger 26 and each type carrier is a toggle-joint connection of special construction. Each type carrier has a link 30 pivotally connected thereto at 31, and each link 75 is pivotally connected at 32 to two links 33 and 34. The link 34 is pivotally connected at one end to the frame at 35, while the link 33 is pivotally connected at its inner end to a head 36 secured to the upper end of the plunger. With this arrangement, the upward movement of the plunger from the position shown in Fig. 1 will act through the links 33, 34 and 30 to move each type carrier inwardly toward the center as seen 85 in Fig. 8, while the downward movement of the plunger into the position shown in Fig. 1 will force the type carriers outwardly into printing position in contact with the platens. This is the position shown in 90 Fig. 1.

Means are provided for inking the type at each reciprocating movement of the type carriers. For this purpose, we have provided an inking plate 37 pivotally mounted 95 on a bracket 38 which is secured to and extends above each type carrier. The ink is transferred from each inking plate to the type by means of ink rolls 39 which are carried by swinging arms 40 that are pivotally 100 mounted at 42 to a bracket 41 carried by the base portion or foot of the type carrier. Each arm 40 has a link 44 pivotally connected thereto at 43, said links being in turn pivotally connected to the guideways 14 at 105 45. As the type carriers move inwardly toward the center, the links 44 will cause the arms 40 to swing downwardly about their pivotal points 42 and thus cause the ink rolls to move down over the type. The ink 110 rolls are guided in their movement by tracks or guides 46 so that they will contact only with the type characters. The ink rolls are yieldingly carried by the arms 40, as usual in printing machines, and will thus be yieldingly held against the tracks and type plate. 115

Means are provided for rotating each ink plate intermittently so as to secure an even distribution of the ink, and for this purpose a spring arm 47 is provided for each ink 120 plate, each arm being secured to a fixed support and adapted to engage a ratchet 48 rigid with the ink plate as the type carrier reciprocates.

Means are provided for rotating the platen 125 support 3 intermittently so as to bring each platen successively into printing position with relation to each type carrier, and while any suitable mechanism for thus intermittently rotating the platen support 3 may 130

be employed, we prefer to accomplish this by mechanism operated from the driving shaft 27. Said driving shaft is formed at one end with a crank 49 having a crank pin 50 which operates in a slot 51 formed in a lever 52 that is pivotally secured at 53 to the frame 1. The upper end of this lever is in the form of the cylindrical pin 54 and is slidably mounted in a block 55 that in turn is pivotally secured to an extension 56 formed on a pawl-carrier 57 in the form of a ring that encircles the standard 1. The block 55 is received within a skeleton member 59 and is provided with the oppositely-disposed trunnions 58 which are pivotally mounted in said member 59. Said member 59 in turn is received within an opening 60 formed in the extension 56 and is provided with the oppositely-disposed trunnions 61 that are journaled in said extension. This makes a universal-joint connection between the end 54 of the lever and the pawl-carrier 57. The pawl-carrier has an actuating pawl 62 pivotally connected thereto at 63, said pawl being adapted to coöperate with lugs or projections 64 carried by the platen-supporting member 3.

The pawl 62 has a notch 99 adapted to receive the lugs 64. There are four of these lugs or shoulders 64 situated at 90° apart, and the operating mechanism for the pawl carrier 57 is such that said pawl carrier will be oscillated through one-quarter revolution, and, therefore, at each oscillation of the pawl carrier, the platen-supporting member will be rotated through 90° . Figs. 1, 7 and 9 show the pawl carrier midway of its return movement. When the pawl carrier has reached the limit of its return movement, the pawl 99 will automatically engage a lug 64, the latter fitting into the notch 99. The platen-supporting member 3 is thus positively locked to the pawl-carrier 57 so that the forward movement of the pawl-carrier will be communicated to the platen-supporting member 3. When the pawl-carrier has completed its forward movement and has turned the platen-supporting member through 90° into the dotted line position, Fig. 7, and full line position, Fig. 11, the pawl is automatically disengaged from the lug 64 thereby to permit the pawl-carrier to have its return movement. This releasing of the pawl 62 is accomplished by means of a pawl-releasing member which is actuated by the crank 49. The pawl has an arm 66 extending therefrom which is provided with a downturned finger 67, as best seen in Fig. 12. Pivoted to the frame 1 is a rock-shaft 68 having a releasing finger 69 fast thereon which is situated in position to engage the finger 67 when the pawl-carrier is at the forward limit of its movement. This rock-shaft 68 has an arm 70 fast thereon which is con-

nected by a link 71 to an arm 72 pivoted at 73 to the frame 1. The crank 49 is formed with a projection 74 which is adapted to engage the arm 72 at each revolution of the crank. The engagement of the finger 74 with the arm 72 will act through the link 71 to rock the shaft 68 and thereby move the releasing finger 69 outwardly in a radial direction. The parts are so timed that this outward movement of the finger 69 occurs just when the pawl-carrier has completed its forward movement and when the finger 67 on the pawl is in position to be engaged by the releasing finger 69. This is the position illustrated in Figs. 11 and 12. The movement of the releasing finger into the dotted line position, Fig. 12, will act through the finger 67 to disengage the pawl from the lug 64. Just as the pawl is thus disengaged, the pawl-carrier begins its return movement, thus carrying the pawl away from the lug 64. The advantage of having a pawl which is positively locked to the lugs, as shown, is that the rotative movement of the platen-supporting member is completely controlled by the pawl. This platen-supporting member has considerable weight, and the forward or feeding movement thereof is a relatively-quick one. The momentum of the platen-supporting member would, therefore, tend to cause it to overrun unless its movement were positively controlled. The form of pawl herein illustrated acts not only to feed the platen-supporting member forward, but also restrains its movement and brings it positively to rest at the end of the forward movement of the pawl-carrier. The pawl is not disengaged from the lug until after the platen-supporting member has been brought to rest and there is, therefore, no possibility that it can overrun.

We have herein shown a friction brake which acts on the platen-supporting member and assists in overcoming the momentum thereof. This brake is in the form of a brake band 80 which surrounds the head 2 of the frame and which is secured to and rotates with the platen-supporting member. One end of the brake band is shown as fastened to a pin 89 secured to one of the arms 5 of the platen-supporting member, and other end of said brake-band is adjustably secured to an adjusting bolt 90 extending from the pin 89.

In order that an accurate printed impression may be made, it is essential that the type carriers should be properly aligned with the platens when they are moved into the printing position shown in Fig. 1. We have, therefore, provided a centering device for each type carrier which becomes operative when the type carrier moves forwardly into its printing position to bring the type carrier into perfect alignment. Each of the

arms 5 of the platen-supporting member is provided with a centering projection 75 and each type carrier is provided with a depending arm 76 having a groove 77 formed in the 5 underside thereof which is adapted to receive the centering projection 75. This groove has the flaring mouth 78 at its outer end, and when the type carrier moves from its rearward position shown in Fig. 8, to the 10 printing position shown in Fig. 1, the lug 75 is caused to enter the groove 77, and by this means the type carrier is held firmly in proper printing position during the printing operation. The advantage of utilizing 15 the quick movement of the pawl-carrier for giving the platen-supporting member its feeding movement is that such feeding movement will occur during a relatively small portion of the time interval required for 20 each cycle of operations, thus allowing the platens to remain at rest during considerably more than half of each time interval and for an appreciable length of time both before and after the type-carriers have 25 moved into printing position.

The machine herein illustrated is especially useful for making a printed impression with a variety of colors. For instance, one type-carrier may carry the type which 30 is to be printed in one color. Another type-carrier may have the type which is to be printed in another color, and so on, and as each type-carrier is separately inked, the type thereon can be provided with any color- 35 ing desired. Hence, with the machine illustrated, it is possible to make a printed impression having four different colors. While the device may be used for various purposes, we find it especially useful in printing 40 labels, such as would be used on the ends of shoe boxes containing the shoes which are to be sold in shoe stores. This printing may either be placed on labels which are pasted on the boxes, or may be placed directly on 45 the box end. The construction of the platen 7 and its supporting bracket 6 is such that a box may be placed over the platen with the end of the box against the platen, in which case the printed impression will be 50 made directly on the box end.

The above reference to the printing of shoe boxes or labels for shoe boxes is only to illustrate one of the many uses to which the machine may be put.

55 The driving shaft 27 may be operated in any suitable way. We have herein shown for this purpose a gear 91 thereon which will be connected to any suitable source of power.

60 While we have illustrated herein a selected embodiment of our invention, we do not wish to be limited to the constructional features shown.

We claim:

65 1. In a marking machine, the combination

with a frame, of a plurality of radially-arranged type carriers thereon, a platen-supporting member rotatably mounted on the frame, a plurality of platens carried thereby, means to rotate the platen-supporting 70 member intermittently to bring the platens successively into printing position relative to the type carriers, means to move the type carriers radially toward and from the platens, an inking roll for inking each type 75 carrier, a pair of arms pivoted to each type carrier at the rear end thereof and in which the inking roll therefor is mounted, and a link pivotally connected at one end to each pair of arms at a point above the pivot for 80 said arms, the other end of said link being pivoted to the frame adjacent the front of the corresponding type carrier whereby the reciprocating movements of the type carriers operate to give movement to the inking rolls. 85

2. In a marking machine, the combination with a frame, of a plurality of radially-arranged type carriers thereon, a platen-supporting member rotatably mounted on the frame, a plurality of platens carried by said 90 member, means to rotate the platen-supporting member intermittently to bring the platens successively into printing position relative to each type carrier, a plunger reciprocable in a direction at right angles to 95 the plane of rotation of the platen-supporting member, a link pivoted to each type carrier, two links pivoted to each of the first-named links and to the plunger and frame, respectively, an inking roll for each type 100 carrier, and means actuated by the movement of the type carriers toward and from the platen to cause the inking roll to ink the type.

3. In a machine of the class described, the 105 combination with a frame, of a plurality of radially-arranged type carriers thereon, a platen-supporting member rotatably mounted on the frame, a plurality of platens carried thereby, means to rotate intermittently the platen-supporting member to bring the various platens successively into operative relation with each type carrier, a plunger reciprocable in a direction at right 110 angles to the plane of rotation of the platen-supporting member, a link pivotally connected to each type carrier, two other links pivotally connected to each of the first-named links and pivotally connected to the plunger and frame, respectively, whereby 115 the reciprocating movements of the plunger cause the type carriers to move toward and from the platens, and means to lock the platen-supporting member from movement while the type carriers are in printing position. 120

4. In a machine of the class described, the combination with a frame, of a plurality of radially-arranged type carriers thereon, a platen-supporting member rotatably mount- 125

ed on the frame, a plurality of platens carried thereby, means to rotate intermittently the platen-supporting member to bring the various platens successively into operative relation with each type carrier, a plunger reciprocable in a direction at right angles to the plane of rotation of the platen-supporting member, a link pivotally connected to each type carrier, two other links pivotally connected to each of the first-named links and pivotally connected to the plunger and frame, respectively, whereby the reciprocating movements of the plunger cause the type carriers to move toward and from the platens, and coöoperating projections on the platen-supporting member and type carriers, respectively, that have interlocking engagement when the type carriers are in operative position thereby locking the platen-supporting member from movement.

5. In a printing machine, the combination with a frame, of a plurality of radially-arranged type carriers thereon, a platen-supporting member rotatably mounted on the frame, a plurality of platens carried thereby and arranged with their operative faces directed toward the type carriers, means to rotate intermittently the platen-supporting member to bring the platen successively into operative relation with each type carrier, a plunger reciprocable in a direction at right angles to the plane of rotation of the platen-supporting member, a link pivotally connected to each type carrier, two other links pivotally connected to each of the first-named links and pivoted to the plunger and frame, respectively, whereby reciprocating movements of the plunger cause the type carriers to move toward and from the platens.

6. In a device of the class described, the combination with a frame, of a plurality of radially-arranged type carriers thereon, a platen-supporting member rotatably mounted on the frame beneath said type carriers, a plurality of platens carried by said member, an oscillatory actuator encircling the frame beneath the platen-supporting member, means to oscillate said actuator, a pawl carried by said actuator, means to cause said pawl to interlock positively with said platen-supporting member during the forward movement of the actuator, a pawl-releasing member situated in a position to engage the pawl at the end of the forward movement of the actuator, and means to operate said pawl releaser in timed relation with the movements of the actuator whereby the pawl will be released from the platen-supporting member at the end of the forward stroke of the latter.

7. In a device of the class described, the combination with a frame, of a plurality of radially-arranged type carriers thereon, a platen-supporting member rotatably mount-

ed on the frame, a plurality of platens carried by said member, an oscillatory actuator encircling the frame beneath the platen-supporting member, a crank shaft journaled in the frame, a lever connection between said crank shaft and actuator whereby the latter is oscillated from the former, a pawl carried by the actuator, means to cause the pawl to have positive interlocking engagement with the platen-supporting member during the forward movement of the oscillator, and means actuated by the crank shaft at the end of such forward movement to release the pawl thereby to permit the actuator to be returned to initial position without moving the platen-supporting member.

8. In a device of the class described, the combination with a frame, of a plurality of radially-arranged type carriers thereon, a platen-supporting member rotatably mounted on the frame, a plurality of platens carried thereby, an oscillatory actuator encircling the frame, a crank shaft journaled in the frame, a lever connecting said crank shaft and oscillatory actuator, a fulcrum for the lever fixed to the frame, said lever having a sliding pivotal connection with the fulcrum whereby the backward movement of the actuator is more rapid than the forward movement, a pawl carried by said actuator, means to cause said pawl to have positive interlocking engagement with said platen-supporting member during the forward movement of the actuator, and means actuated by the crank shaft to release the pawl at the end of such forward movement.

9. In a marking machine, the combination with a frame, of a plurality of radially-arranged type carriers thereon, a platen-supporting member rotatably mounted on the frame, a plurality of platens carried by said member, means to rotate the platen-supporting member intermittently to bring the platens successively into printing position relative to each type carrier, means to move the type carriers radially toward and from the platen, and a locking device to prevent the platen supporting member from rotative movement, which locking device is rendered operative by the type carriers when they are moved into printing position.

10. In a marking machine, the combination with a frame, of a plurality of radially-arranged type-carriers thereon, a platen-supporting member rotatably mounted on the frame, a plurality of platens carried by said member and situated outside of said type carriers with their operative faces directed toward the center of rotation, means to rotate the platen-supporting member intermittently to bring the platens successively into printing position relative to each type carrier, means to move the type carriers radially toward and from the platens, and means carried by the type carriers to

lock the platen-supporting member from rotative movement while said type carriers are in printing position.

11. In a marking machine, the combination with a frame, of a plurality of radially-arranged type-carriers thereon, a platen-supporting member rotatably mounted on the frame, a plurality of platens carried by said member and situated outside of the type carriers, means to rotate the platen-supporting member intermittently to bring the various platens successively into printing position relative to each type carrier, means to move the type-carriers radially toward and from the platens, and coöperating projections carried by the platen-supporting member and type-carriers, respectively, and adapted to be brought into interlocking engagement when the type-carriers are moved into printing position thereby to lock the platen-supporting member from rotative movement.

12. In a marking machine, the combination with a frame, of a plurality of radially-arranged type carriers thereon, a platen-supporting member rotatably mounted on the frame and having a plurality of radially-extending arms, a platen mounted on each arm, means to rotate the platen-supporting member intermittently to bring the platens successively into printing position relative to each type carrier, means to move the type-carriers toward and from the platen, a centering projection carried by each arm of the platen-supporting member, and a grooved block carried by each type carrier and adapted to be brought into interlocking engagement with one of the centering projections when the type carrier is moved radially into printing position. 40

In testimony whereof we have signed our names to this specification.

FRED A. PUTNAM.

CHARLES F. ROBBINS.
